(57) **CLAIM**

The ornamental design for fire detector as shown and described.

DESCRIPTION

FIG. 1 is a front, top perspective view of a fire detector showing my design.

FIG. 2 is a top plan view thereof.

FIG. 3 is a bottom plan view thereof.

FIG. 4 is a right side view thereof, the left side being a mirror image thereof; and,

FIG. 5 is a front elevation view thereof, the rear elevation view being a mirror image thereof.

The dash-dash lines illustrate unclaimed environmental matter only and form no part of the claimed design.

1 Claim, 5 Drawing Sheets
